UNITED STATES PATENT OFFICE.

JOSEPH BEVARD, OF WOOSTER, OHIO.

GIG-SADDLE.

SPECIFICATION forming part of Letters Patent No. 274,260, dated March 20, 1883.

Application filed December 30, 1882. (No model.)

To all whom it may concern:

Be it known that I, JOSEPH BEVARD, of Wooster, in the county of Wayne and State of Ohio, have invented a new and useful Improvement in Gig-Saddles, of which the following is a full, clear, and exact description.

Reference is to be had to the accompanying drawings, forming part of this specification, in which similar letters of reference indicate corresponding parts in all the figures.

Figure 1 is a sectional front elevation of a gig-saddle made in accordance with my invention. Fig. 2 is a plan view of one side of the saddle with the outside strap removed, showing the opening through which the terret-nut may be put in place and removed without ripping or cutting the pad, and Fig. 3 is an inverted broken plan view of one side of the saddle with the cushion removed, showing the pocket for the terret-nut, the opening through which it is put in place and removed, the metal plate and the nuts for receiving the terret, and ordinary screws by which the skirt and tree are secured to the saddle.

A represents the skirt of the saddle; B, the pad or cushion; C, the outside strap; E, the tree, and F the terrets.

The pad B is formed of the leather outer portion, a, inner cloth portion, b, and stuffing c. To the inner surface of the outer portion, a, of the pad is secured, by small tacks or nails, the curved metal plate G, which serves to give form to the saddle. Near the upper end of this plate is formed a depression and opening, g, in which the terret-nut d is placed, which is adapted to receive the screw-shank of the terret F, for securing the tree E, skirt A, outer strap, C, and the terret itself together. f is the lower nut for holding the lower end of the pad B and the skirt A together. This nut is secured to the inner surface of the outside portion, a, of the pad, preferably by small nails, and is adapted to receive the screw-threaded portion of the screw H, which secures the pad

and skirt together, the head of which screw is 45 covered and wholly concealed by the outside strap, C, as will be understood from Fig. 1.

h is an opening made through the outer portion, a, of the pad, and is for the purpose of permitting the insertion of the terret-nut d into and its removal from the pad without cutting or otherwise defacing the pad. The nut will be inserted between the skirt A and the outer portion, a, of the pad, and will be held in the pocket i, formed by the strip of leather J, 55 tacked over the plate G and opening h, as shown in Figs. 1 and 3. Without this opening h the under part of the pad would have to be cut to change the nut, which would injure the pad and at the same time require considerable time and labor, whereas by my method the nut may be very quickly and easily changed without in any manner harming the pad.

A gig-saddle constructed in this manner is 65 very compact and solid and strong, and all the screws used are concealed; and the saddle is very cheap, since no extra loops or short straps or other separate fastenings are required for securing the parts together.

Having thus described my invention, what I claim as new, and desire to secure by Letters Patent, is—

1. The combination, with the pad B, the terret F, and nut d, of the curved metal plate G, 75 having a countersunk opening, g, and secured to the inner surface of the pad, substantially as herein shown and described.

2. The pocket i, formed near the top of the saddle by the outer part, a, and the strip or 80 piece of leather J, for receiving the terret-nut, the part a being formed with opening h, through which the nut may be inserted and removed without injury to the pad, as set forth.

JOSEPH BEVARD.
